UNITED STATES PATENT OFFICE.

EUGENIO BEOVIDE, OF MINERAL DE CATORCE, MEXICO.

MACHINE FOR CLEANING AND SEPARATING THE FIBERS OF LEAVES.

SPECIFICATION forming part of Letters Patent No. 251,818, dated January 3, 1882.

Application filed August 31, 1881. (No model.)

To all whom it may concern:

Be it known that I, EUGENIO BEOVIDE, of Mineral de Catorce, Mexico, have invented a new and Improved Machine for Cleaning and Separating the Fibers of Leaves, of which the following is a specification.

The object of my invention is to provide a new and improved machine for removing the epidermis and filling cellular tissue from the fibers of such leaves as those of the *Agave Americana*, or aloe, *Heniquen zechuquitta marquisia*, or *Coprosma*, and other plants growing in Mexico, Central and South America, which fibers are then used in the industries in the same manner as hemp and jute fibers, &c.

The invention consists of a frame in which two or more rollers provided with yielding, rasping, and scraping knives and with yielding, feeding, and pressing blades guided by suitable guide-rings on the frame are journaled above each other and are surrounded by suitable casings, into the upper one of which the leaves are fed from an inclined table by adjustable feed-rollers and are drawn downward through the several receptacles by adjustable feed-rollers journaled between each pair of rasping-rollers. The rasping-rollers revolve very rapidly and scrape all cellular matter from the fibers, this waste being thrown out through openings in the casings and the cleaned fibers passing out between two rollers below the lowest rasping-roller.

The invention further consists in a rasping-roller provided with a series of radial longitudinally-grooved wings containing radially-movable rasping and scraping knives and feeding and pressing blades, which are pressed outward radially by springs contained in recesses in these wings.

The invention further consists in the combination, with the scraping and pressing rollers, of cog-wheels, shafts, and pinions for rotating the several parts at the various speeds required.

The invention also consists in the arrangements and construction of parts and details, as will be more fully described hereinafter.

Reference is to be had to the accompanying drawings, forming part of this specification, in which similar letters of reference indicate corresponding parts in all the figures.

Figure 1 is a rear elevation of my improved machine for cleaning and separating the fibers of leaves from the surrounding tissues. Fig.

2 is a longitudinal sectional elevation of one of the scraper-rollers of the machine, showing the scraper-knives in elevation. Fig. 3 is an end elevation of the machine. Fig. 4 is a longitudinal sectional elevation of the scraper-roller, showing the feeding and pressing blades in elevation. Fig. 5 is a detail sectional elevation of part of one blade and its spring. Fig. 6 is a longitudinal elevation of the bearing and its adjusting-spring for one pair of feed-rollers. Fig. 7 is a longitudinal elevation of one of the bearings of a rasping or scraping roller. Fig. 8 is an end elevation of the machine, the cog-wheels being removed. Fig. 9 is a cross-sectional elevation of the rasping or scraping roller on the line *y y*, Fig. 4. Fig. 10 is a cross-sectional elevation of the same on the line *z z*, Fig. 4. Fig. 11 is a cross-sectional elevation of the machine on the line *x x*, Fig. 1. Fig. 12 is a longitudinal elevation of one of the rasping or cutting rollers. Fig. 13 is a partial longitudinal sectional elevation of one of scraper-rollers, showing the pressing or feeding knives in elevation.

A rasping or scraping roller, A, is formed of a shaft, A', provided with a series of radial and longitudinal wings, A², which are grooved longitudinally and contain either a blade, B' or B², these blades being held in the grooved wings by screws or pintles *a* passing through the grooved wings and through transverse slots *b* in the blades, thus permitting a radial movement of the blades. Spiral springs B are contained in recesses A³ formed in the grooves of the wings A², and each has a centrally-apertured cap, B³, as shown in Figs. 5 and 10, resting on the outer end, which cap fits into a recess, *c*, in the edges of the blades B' or B², and a projection, *c'*, in the middle of the inner edge of this recess passes into the aperture *c'* of the cap B³, and thus holds the cap in the recess, as clearly shown in Fig. 5. The several springs, B, acting on a blade, B' or B², press this blade outward. The blades B' serve to rasp and scrape and have a beveled outer edge, and the blades B² serve to press and push or feed the leaves and are provided at the outer edge with a longitudinal head or rib, B⁴, having a triangular cross-section, as shown in Figs. 9 and 10. I prefer to have two opposite rasping or scraping blades, B', and two opposite pressing or feeding blades, B², on each scraper-roller A.

The ends of the presser-blades B² extend to the inner surface of the end walls, C', of the

wings A^2 , as do the rasping-blades B' also; but the latter have a projection, C , at the upper edge at each end, the end of this projection being flush with the outer surface of the end wall of the wing, as shown in Fig. 2. The outer or upper edge of the projection C is rounded. Two or more of these scraper-rollers A are arranged above each other and separated a certain distance in frames $D' D^2$, the shafts A' of these rollers being journaled in bearings D attached to the outer sides of the frames $D' D^2$ and across openings E in these frames, into which openings the ends of the scraper-rollers pass. The openings E are of such diameter as to admit the scraper-rollers A when the projections C of the blades B' rest on the outer edges of the end walls, C' , of the wings, as is shown in Fig. 2.

Each scraper-roller A is surrounded by a cylindrical casing, F , of precisely the same diameter as the apertures E . These casings F have a longitudinal opening, F' , at one side and a longitudinal opening, F^2 , at the bottom. The uppermost casing F has a longitudinal opening or slot, F^3 , in the side opposite the opening F' , but has no top opening; but the lower casings F are not provided with this second side opening, F^3 , but have a longitudinal top opening, F^4 . The bottom openings, F^2 , extend throughout the entire length of the casing F , but the side and top openings, $F' F^4$, are not quite as long as the casings, so that short segmental ridges I will project from the inner surface of the walls $D' D^2$, for a purpose that will be specified hereinafter.

Two fluted feed-rollers, $G G$, are journaled in front of the opening F^3 of the upper casing F and parallel with this casing, so that these rollers $G G$ will feed the leaves from an inclined table, H , into the uppermost casing F through the opening F^3 . Two smooth feeding-rollers, J , are mounted on shafts $J' J^2 J^3$, respectively journaled in the frames $D' D^2$, between each two casings F , in such a manner that the lines of the peripheries of these feed-rollers J will be in contact with the inner periphery of the casing F above each set of rollers, but will be about half of an inch from the inner periphery of the casing F below each set of rollers, as is clearly shown in Fig. 11. The feed-rollers J will thus almost fill the bottom or lower opening, F^2 , of each casing F . The feed-rollers G and J all have one journal-box, g , fixed, and the other journal-box, h , made movable, these movable journal-boxes h being adjusted by means of a spiral or rubber spring, K , and a set-screw, L . Both the fixed and sliding journal-boxes are held in a frame, L' .

The shafts A' of the rasping or scraping rollers A all project from the frame D' , and on each shaft A' a cog-wheel, M , is rigidly mounted, these cog-wheels engaging with each other and being of the same size.

On the uppermost shaft A' a pulley, N , for a driving-belt is mounted, and on the lowest shaft A' is mounted a pinion, O , engaging with a large cog-wheel, P , mounted on a shaft, P' ,

on the opposite end of which is also mounted a small cog-wheel, P^2 , engaging with a cog-wheel, Q , mounted on a shaft, Q' , on which is mounted a pinion, Q^2 , engaging with a large cog-wheel, R , mounted on the shaft J^3 of the driving-roller J of the lowest set of feed-rollers J . On this shaft J^3 a cog-wheel, R^3 , and a pinion, S^3 , are mounted, the pinion engaging with a pinion, T^3 , on the shaft of the adjustable roller J , and the cog-wheel R^3 engaging with a cog-wheel, R^2 , on the shaft J^2 of the roller with the fixed bearing of the second set of feed-rollers. On this shaft J^2 a pinion, S^2 , is mounted, engaging with a pinion, T^2 , on the shaft of the corresponding adjustable feed-roller. The wheel R^2 engages with a cog-wheel, R' , on the shaft J' of the roller with the fixed bearing of the uppermost set of feed-rollers J , and a pinion, S' , mounted on this shaft J' engages with a pinion, T' , on the corresponding adjustable feed-roller J . A cog-wheel, U , mounted on the shaft J' , engages with a cog-wheel, V , on the shaft G' of the upper fluted feed-roller G . A pinion, W , on this shaft G' engages with a pinion, X , on the shaft G^2 of the lower roller G . As each alternating scraping or rasping roller A rotates in opposite directions the openings F' of the casings F must alternately be in the front and rear of the machine.

The operation is as follows: The leaves, stems, &c., are passed down the inclined table H , in between the fluted rollers G , which seize them and pass them transversely through the opening F^3 into the uppermost cylinder F . The presser-blades B^2 and the scraper-blades B' will immediately seize the leaves and draw them inward, and the leaves will be pressed against the inner sides of the casing F . The roller A revolves about two thousand times per minute and tears and breaks the epidermis and cellular filling matter of the leaves and scrapes them from the fibers and throws this waste out through the opening F' . Gradually the entire leaf is drawn into the casing F , and all the epidermis, &c., of one side of the leaf is removed—that is, from that side exposed to the action of the blades $B' B^2$. As has been previously stated, the presser-blades B^2 are shorter than the scraper-blades and the aperture F^2 is longer than the other apertures of the casing F . The presser-blades B^2 are pressed into their corresponding grooved wings by the inner sides of the casings F and by the segmental ridges I formed at the ends of the openings F' , F^3 , and F^4 ; but as there are no such ridges at the ends of the openings F^2 the springs B can press the presser-blade downward in between the rollers $J J$ every time the presser-blade arrives at this opening F , as shown in Fig. 13. As the head or rib B^4 of each presser-blade is beveled, the outer edge of the presser-blade will not catch on the roller J , but will slide up the same, and when the edge of the presser-blade arrives at the longitudinal edge of the opening F^2 it is pressed back into its grooved wing A^2 , and again

shoots outward when arriving at this opening, &c. The rasping or scraping blade B' cannot pass in between the rollers J, for the projections C project even beyond the ends of the opening F², and thus hold the knife within the aperture E. This is absolutely necessary, as the blades B' would cut and tear the leaves and fibers if they had the same movements as the presser-blades B². By passing in between the rollers J J this presser-blade presses the fibers or those parts of the leaves that have not been thrown out through the opening F' of the upper casing F in between the feed-rollers J, which catch them and pass them into the next lower casing. The rasping or scraping cylinder of the second casing F revolves in the inverse direction of the rasping-roller of the uppermost casing F. The other side of the leaf is thus rasped and scraped and the fibers are again seized by feed-rollers J and passed into the next lower casing F, where all the remnants of the epidermis or cellular matter are removed and the cleaned fiber is seized by the rollers J of the lowest casing F and are ejected.

If desired, more than three scraping or rasping rollers may be used, as the circumstances may require.

It will be observed that the gearing is so arranged that the feed rollers J rotate about one-fiftieth as fast as the scraping-rollers A, thus permitting the blades to act on the leaves a certain time before these leaves are removed from one casing into another. The fibers obtained are about eight to twelve inches long and resemble hemp or jute fibers.

The edge of the blades B' must not be sharp, but are preferably dulled or rounded so as to rasp and scrape and not cut. The springs B must be powerful enough to press the blades on the leaves with sufficient force to break and tear the epidermis without breaking or cutting the fiber. The rollers J have their lowest point slightly above the highest point of the next lower casing F, so that the leaves can pass into the lower casing F more conveniently and without producing undue resistance or friction.

Having thus fully described my invention, I claim as new and desire to secure by Letters Patent—

1. In a machine for cleaning the fibers of leaves and plants, the combination, with the roller A, provided with the longitudinally-grooved wings A², the springs B, and the means for securing them in the said grooved wings, of the rasping or scraping blades B', having beveled outer edge, and the pressing or feeding blades B², provided with heads B⁴, triangular in cross-section, substantially as and for the purpose set forth.

2. In a rasping or scraping roller, A, for machines for cleaning the fibers of leaves and plants, the combination, with the shaft A' and the longitudinally-grooved radial wings A², provided with recesses A³, of the blades B' B², provided with recesses e, the springs B, and

the caps B³, substantially as herein shown and described, and for the purpose set forth.

3. In a machine for cleaning the fibers of leaves and plants, the combination, with the rotating cylinder, provided with spring-supported rasping or scraping blades B', formed with projections C, of the endcasing, C', formed with apertures into which the said projections extend, substantially as and for the purpose set forth.

4. In a machine for cleaning the fibers of leaves and plants, the combination, with the frames D' D², provided with apertures E, and the casings F, having the same diameter as the apertures E, the rasping or scraping rollers A, contained in the casings F, of the feed-rollers J J, located between the casings F, and of gearing for operating the rasping or scraping rollers and the feed rollers, substantially as herein shown and described, and for the purpose set forth.

5. In a machine for cleaning the fibers of leaves and plants, the cylindrical casings F, constructed, substantially as herein shown and described, with a bottom longitudinal opening, F², extending throughout the entire length of the casing, with a top longitudinal opening, F⁴, extending to within a short distance from the ends of the casing, and with a longitudinal side opening, F', extending to within a short distance of the ends of the casing and forming segmental ribs I on the inner sides of the frames D' D², substantially as herein shown and described, and for the purpose set forth.

6. In a machine for cleaning the fibers of leaves and plants, the combination, with the casings F, of the feed-rollers J, located between two casings in such a manner that the periphery of the rollers J will touch the inner periphery of the casing F above the feed-rollers and will be a short distance above or from the inner periphery of the casing F below the feed-rollers, substantially as herein shown and described, and for the purpose set forth.

7. In a machine for cleaning the fibers of leaves and plants, the combination, with the frames D' D², of the rasping and scraping rollers A, the feed-rollers J and G, the casings F, the cog-wheels M, the pinion O, the cog-wheel P, the shaft P', the cog-wheels P² Q, the pinion Q², the cog-wheels R R' R² R³, the pinions S' T' S² T² S³ T³, the cog-wheels U and V, and the pinions W and X, substantially as herein shown and described, and for the purpose set forth.

8. In a machine for cleaning the fibers of leaves and plants, the combination, with the rasping or scraping rollers A, the feed-rollers J, and the casings F, of devices for rotating the rasping or scraping rollers with a much greater rapidity than that of the feed-rollers, substantially as herein shown and described, and for the purpose set forth.

EUGENIO BEOVIDE.
